United States Patent Office

Des. 176,308

Patented Dec. 13, 1955

176,308

CRUMB SWEEPER

Paul G. Caisse, Hartford, Conn., assignor to The Fuller Brush Company, Hartford, Conn., a corporation of Connecticut

Application May 16, 1955, Serial No. 35,994

Term of patent 14 years

(Cl. D9—2)

Fig. 1.

Fig. 2.

Fig. 3.

Fig. 1 is a plan view of a crumb sweeper showing my new design;

Fig. 2 is a front view of said crumb sweeper;

Fig. 3 is an end view of said crumb sweeper.

I claim:

The ornamental design for a crumb sweeper, as shown.
